INSULATING CONTAINER

G. John Heelan, Olympia, Wash., assignor to Olympia
Brewing Company, Olympia, Wash.

Filed June 8, 1972, Ser. No. 261,147

Term of patent 14 years

Int. Cl. D9—03

U.S. Cl. D9—187

FIG. 1

FIG. 3

FIG. 2

FIG. 1 is a perspective view of an insulating container showing my new design;

FIG. 2 is an exploded view showing the interior of both halves;

FIG. 3 is a bottom plan view on a reduced scale; and

FIG. 4 is an enlarged, perspective view of the closure plug.

The sides opposite those seen in FIG. 1 are the same in appearance as the respective sides shown.

I claim:

The ornamental design for an insulating container, as shown and described.
